DESIGN FOR A TABLE

Frank C. Castelli, Carroll Park, Pa., assignor to F. C. Castelli Company, Philadelphia, Pa., a corporation of Pennsylvania

Application February 25, 1948, Serial No. 144,730

Term of patent 3½ years

(Cl. D33—14)

To all whom it may concern:

Be it known that I, Frank C. Castelli, a citizen of the United States, residing at Carroll Park, in the county of Delaware and State of Pennsylvania, have invented a new, original, and ornamental Design for a Table, of which the following is a specification, reference being had to the accompanying drawings, forming a part thereof.

In the drawings, Fig. 1 is a perspective view of the table taken from the front and side; Fig. 2 is a side elevational view of the table; Fig. 3 is an enlarged fragmentary perspective view, looking in the direction indicated by the line 3—3 of Fig. 1, of a part of the frame showing my new design.

I claim:

The ornamental design for a table, as shown.
FRANK C. CASTELLI.
